UNITED STATES PATENT OFFICE.

CHARLES H. HARNELL, OF UNION TOWNSHIP, MONTGOMERY COUNTY, INDIANA

SECTIONAL BURIAL-VAULT.

1,253,174.

Specification of Letters Patent.

Patented Jan. 8, 1918.

Application filed August 18, 1916. Serial No. 115,655.

To all whom it may concern:

Be it known that I, CHARLES H. HARNELL, a citizen of the United States, residing in Union township, in the county of Montgomery and State of Indiana, have invented a new and useful Sectional Burial-Vault, of which the following is a specification, reference being had to the accompanying drawings and to the letters and figures of reference marked thereon.

This invention relates to the type of burial vault that is designed to be shipped in knock-down condition and to be set up at the place where it is to be used, the invention having reference more particularly to a burial vault structure that may suitably be composed of concrete or various plastic compositions.

An object of the invention is to provide an improved sectional burial vault of such construction as to be composed of the minimum number of simple patterns adapted to be interchangeably connected together. Another object is to provide an improved sectional burial vault that shall be so constructed as to be adapted for use not only in dry ground but in wet earth and without causing troublesome preparation which in many cases is necessary in order to prevent entrance of water into the vault while being erected. A further object is to provide improved burial vault sections of such construction that they may be handled without liability to fatal injury to the joint portions thereof. A still further object is to provide improved burial vault sections and improved means for securing the sections together, an aim being to provide an inexpensive, durable and economical burial vault.

With the above mentioned and other objects in view, the invention consists in a sectional burial vault having certain novel features of construction; the invention consisting further in the novel parts and combinations and arrangements of parts as herein-after particularly described and further defined in the accompanying claim.

Referring to the drawings,—Figure 1 is a perspective view of a burial vault constructed substantially in accordance with the invention. Fig. 2 is a transverse central sectional view of the improved vault. Fig. 2 is a top plan of the bottom and the side wall of the vault set up but not cemented together. Fig. 4 is a perspective view of one of the cover sections of the vault inverted.

Fig. 5 is a perspective view of the improved joint-locking means. Fig. 6 is a perspective view of one of the intermediate cover sections inverted. Fig. 7 is a longitudinal central section of the improved vault. Fig. 8 is a top plan of the bottom of the vault. Fig. 9 is a fragmentary section of the vault on the line IX—IX of Fig. 3. Fig. 10 is a fragmentary section on the line X—X of Fig. 3. Fig. 11 is a perspective view of one of the end sections of the wall of the vault, and Fig. 12 is a fragmentary perspective view of one of the side sections of the wall of the vault.

Similar reference characters on the different figures of the drawings indicate like parts or features of construction herein referred to.

In practically carrying out the objects of the invention a suitable number of bottom sections of slab shape are provided, there being preferably two end sections 1 and 2 and a middle section 3. The end sections are alike in form so that one mold is sufficient for making both sections. The top of one section has an end groove 4 and side grooves 5 and 6 therein that extend continuously adjacent to the edges of the sections, the companion end section having similar grooves 4', 5', 6'. The middle section has grooves 7 and 8 in its top that are spaced apart equal to the distance between the grooves 5 and 6 so as to form continuations thereof. The middle section may be made in different lengths so as to provide a vault of the length that may be required for graves of adults; and also when considerable variation in length is necessary the end sections may be made in various lengths. The bottom sections have plain joint edges and the tops of the end sections adjacent to the joint edge have recesses 9, 9', the middle section having similar recesses 10, 10', adjacent to its joint edges to receive plaster or cement. One end section has sockets 11 and 12 that extend from the bottom of the grooves 5 and 6 respectively in proximity to the joint edge of the section, the middle section 3 having similar sockets 13 and 14 that extend from the bottom of the grooves 7 and 8 adjacent to one joint edge of the section. The other end section has sockets 11' and 12' adjacent to its joint edge, the middle section having sockets 13' and 14' adjacent to its opposite joint edge. A suitable number of joint locks are provided

which are in the form of staples, two staples 15 and 15' being placed so as to lock the section 1 to the section 3, the legs of the staples being inserted in the sockets of the 5 respective sections; and similar staples 16 and 16' are placed so as to secure the section 2 to the section 3, the legs of the staples being inserted in the sockets of the respective sections. The recesses 9 and 10 are 10 filled with plaster or cement 17, the recesses 9' and 10' being filled with similar substance 18 in order to close and seal the adjacent joints.

In order to accurately place the wall sections of the vault on the vault bottom and securely retain them in position the groove 4 has sockets 19, the grooves 5 and 6 having sockets 20 and 21, the groove 4' having sockets 19', the grooves 5' and 6' having sockets 20' and 21' respectively; and the grooves 7 and 8 have sockets 22 and 23 therein respectively. Some of the sockets have metallic dowel-pins 24, 24' therein, others having similar pins 25, 25' therein. The dowel-pins 25 are securely embedded and secured in the sockets by means of plaster or cement 26, 26' placed in the groove 4 and 4' respectively. The dowel-pins for the side sections of the wall are secured in place by means of plaster or cement 27 and 28 placed in the grooves 30 that extend along the side edges of the sections.

The wall of the vault comprises two side sections 29 and 30 of suitable length, one section preferably being longer than the other, two similar side sections 31 and 32, and two end sections 33 and 34, the end sections being alike but arranged in reverse order upon the bottom of the vault. The 40 section 31 is arranged opposite to the longer section 29, the section 30 being arranged opposite to the longer section 32, so that the joints between the sections of the side walls are not on one and 45 the same plane. The bottoms of the wall sections are flat and are placed upon the mortar or cement which is placed in the grooves that are formed in the top of the bottom sections. The bottoms of the end 50 sections 33 and 34 have sockets 35 and 35' therein respectively that receive the dowel-pins 25 and 25' respectively. The bottoms of the side wall sections have sockets 36, 36' that receive the dowel-pins 24, 24' arranged for the purpose of securing the side 55 wall sections. The vertical ends of the wall section 29 have vertical grooves 37 and 38 therein respectively, the end of the section 30 that abuts the section 29 having a vertical 60 groove 39 therein, the opposite end of the section 30 having a similar groove 40 therein. The end of the section 31 that abuts the end section 33 has a vertical groove 40' therein, the opposite end of the section having a similar groove 39' therein. The end 65

of the section 32 that abuts the end section 34 has a vertical groove 37' therein, the opposite end having a similar groove 38' therein. The inner side of the end section 33 has vertical grooves 41 and 42 therein 70 that are in register with the grooves 37 and 40' respectively. The inner side of the end section 34 has vertical grooves 41' and 42' that register with the grooves 37' and 40' respectively. The grooves 38 and 39 75 being in register form an opening that extends from the top of the side wall to the bottom thereof, and a rod 43 is placed in the opening in vertical arrangement. A similar rod 44 is placed in the opening 80 formed by the grooves 37 and 41, a similar rod 44' being placed in the opening formed by the grooves 40' and 42. A rod 43' is placed in the opening formed by the grooves 38' and 39', a similar rod 45 is placed in the 85 opening formed by the grooves 37' and 41', a similar rod 45' being placed in the opening formed by the grooves 40 and 42'. The rods preferably are each provided with an anchoring foot 46 on its lower end. A suitable number of key blocks 47, 47' are placed 90 on each rod in spaced apart order, each key block having a central aperture 48 therein to receive the rod. Plaster or cement 49, 49' is placed in the openings between the key blocks and when hardened forms a water tight joint between each two adjacent sections while the key blocks constitute very strong joint locks.

In order to insure tight sealing of the 100 cover on the wall of the vault without the use of delicate portions that might be broken off in handling the sections, the top of the end section 33 has a longitudinal groove 50 therein that intersects the vertical 105 grooves 41 and 42, the end section 34 of the wall having a similar groove 50' in its top. The section 29 likewise has a longitudinal groove 51, the like section 32 having a groove 51' therein. The section 31 110 has a groove 52 in its top, the like section 30 having a similar groove 52' in its top. The groove in the top of each section of the side walls extends from the vertical grooves 115 in the ends of the section. The section 33 has sockets 53 therein that extend from the bottom of the groove 50, the section 34 having sockets 53' that extend from the bottom of the groove 50'. The section 29 has 120 sockets 54 that extend from the bottom of the groove 51, the section 32 having similar sockets 54'. The section 31 likewise has sockets 55, the section 30 having similar sockets 55'. Dowel-pins 56 and 56' are inserted in the sockets 53 and 53' respectively, similar dowel-pins 57 and 57' being inserted in the sockets that are provided in the sections of the side walls. The grooves 50 and 50' are filled with plaster or cement 58 and 58' respectively, the grooves in the top of 130

the sections of the side walls being filled with plaster or cement 59 and 60 respectively.

A suitable number of arched cover sections are provided, there being two similar end sections, one comprising two sloping portions 61 and 62 the other comprising similar sloping portions 61' and 62', the end sections having wall portions 63 and 63' respectively. Intermediate sections 64, 64', 64" are provided that correspond with the sloping portions of the end sections. The wall portions of the end sections have sockets 65 and 65' to receive the dowels 56 and 56' respectively, the lower ends of the sloping portions having similar sockets 66 and 66' to receive the dowels 57, 57'. The top of each end section has a recess 67 adjacent to the joint edge thereof, the top of the intermediate section having each a recess 68 adjacent to one joint edge and a similar recess 68' adjacent to the opposite joint edge thereof, and when the cover sections are placed together upon the side wall the recesses are filled with plaster or cement 69 to close and seal the joints between the sections of the cover. Each cover section is provided on its top with an eye 70 for lowering the section into place.

In order that the vault may be erected in wet ground the middle one of the floor sections has a well-opening or man-hole 71 which is larger in diameter in its upper portion than in its lower portion so that a ledge 72 is formed which supports a door 73 having a ring 74 on its top for handling it, the door being sufficiently thin so as to leave space above it in which cement 75 is placed to seal the well-opening. When there is considerable water in the ground 76 where the vault is to be placed a well or catch-basin 77 is dug so as to be below the middle of the bottom of the vault and accessible through the well-opening.

It should be understood that the various sections are made in a variety of sizes and

so as to be interchangeably used with other sections for different sizes of vaults, so that when a vault of a particular size is required it is only necessary to select the proper sections to obtain the required vault dimensions.

In practical use the several sections are readily placed in position without requiring extraordinary means for handling them. In case the water in the ground is sufficient to interfere with the sealing of the joints the well or catch-basin is dug to receive the water which is bailed out through the well-opening 71, the latter being subsequently closed and sealed. In some cases when the grave is dug in dry ground the well-opening may be left unclosed for drainage purposes. It will be understood that after the cover is placed and sealed upon the wall of the vault to inclose the casket as designed the devices 70 may be removed from the cover before filling in the earth over the vault.

Having thus described the invention, what is claimed as new is—

A burial vault comprising a bottom, a plurality of wall sections continuously arranged upon the bottom, each section having joint portions in contact with like portions of adjacent sections, each joint portion having a vertical groove therein, the grooves of each two adjacent portions forming an opening extending down from the top of the wall, rods vertically arranged in the openings respectively and having each a plurality of key blocks thereon that extend into the vertical grooves of the adjacent joint portions, plastic material in said openings enveloping said blocks and rods, and a cover for the wall sections.

In testimony whereof, I affix my signature in presence of two witnesses.

CHARLES H. HARNELL.
